JOURNAL TURNING, QUARTERING, AND CRANK PIN TURNING MACHINE

Augustus Wood, Hamilton, Ohio, assignor to General Machinery Corporation, Hamilton, Ohio, a corporation of Delaware

Application November 15, 1940, Serial No. 365,811

13 Claims. (Cl. 77—21)

This invention relates to machines for turning inside or outside journals of a wheel set for a locomotive and for quartering and turning the crankpins of the driving wheel sets.

Various machines have heretofore been produced for accomplishing the various operations of journal turning, quartering and pin turning of wheel sets for locomotives. The machines have either been individual machines for accomplishing the various operations or there have been certain disadvantages connected with a single machine for accomplishing these various operations.

It is an object of this invention to provide a single machine which is capable of performing all of the necessary operations of journal turning, quartering and pin turning with greater safety and less inconvenience than has heretofore been capable of performance upon combination machines.

Another object of the invention is to provide a combination machine wherein the quartering and pin turning operations of the wheel set can be accomplished with the counterweights of the wheel set positioned in their least dangerous position, and for subsequently turning the journals on the wheel set.

It is another object of the invention to provide a combination machine for journal turning and quartering a wheel set wherein the counter-balances of the wheel set are positioned in a manner that the effective center of gravity is in substantial vertical alignment with the supporting spindles for the wheel set, and which is capable of turning the journals on the wheel set without removing the same from the machine after the quartering operation.

It is another object of the invention to provide a method for performing the quartering, pin turning and journal turning operations of a wheel set in a manner which will produce the greatest safety of operation of the machine.

It is another object of the invention to provide a method for positioning a wheel set within a metal turning machine in a manner that the wheel set is established therein in its safest position, and for quartering the wheel set while in said position, and to provide for subsequent balancing of the wheel set when turning the journals thereon.

It is another object of the invention to provide an improved apparatus for hoisting the wheel set into position in alignment with the spindles of the machine.

It is another object of the invention to provide an improved apparatus for holding the same

against rotation when the wheel set is supported by the spindles of the machine.

It is another object of the invention to provide a clamping apparatus upon a metal turning machine for locomotive wheel sets which will not displace the parallelism of the wheels while being quartered, or during pin turning.

It is still a further object of the invention to provide an improved adjusting device for rotationally positioning the wheel set in an accurate manner for the quartering operation, and for pin turning.

It is still a further object of the invention to provide a clamping device for a wheel set which is adjustable in a manner that wheels of varying diameters can be secured against rotation.

Further objects and advantages will become apparent from the following description and from the figures in the drawings.

20 In the drawings:

Figure 1 is a front elevational view of a combined machine for journal turning, quartering, and crank pin turning of wheel sets for a locomotive or car.

25 Figure 2 is an end view of the left-hand end of the machine of Figure 1.

Figure 3 is an end view of the right-hand end of the machine of Figure 1.

30 Figure 4 is an elevational view of a portion of the combined machine showing the mechanism for clamping the wheels against rotation when supported by the turning centers of the machine.

Figure 5 is a cross sectional view taken substantially along line 5—5 of Figure 4.

35 Figure 6 is a cross sectional view of a jack for elevating a wheel set by means of the wheels or tread.

Figure 7 is a top plan view, partially in cross section, of the jack for clamping mechanisms shown in Figures 4 and 6.

40 Figure 8 is a cross sectional view of the clamping mechanism for securing the wheel set against rotation as applied to a wheel of small diameter.

Figure 9 is a plan view of a portion of the 45 adjusting mechanism for rotationally adjusting the wheel set when in the machine, taken substantially along the line 9—9 of Figure 8.

Figure 10 is a perspective elevational view of a wheel set for a locomotive.

50 In this invention the machine is adapted to perform several operations upon a wheel set for a locomotive when producing and finishing the same. The various operations of turning the journals on a wheel set, of quartering the same, and of turning the crank pins thereon have

been most conveniently accomplished when using individual machines. However, the machine of my invention has been constructed and arranged for convenience and economy of operation, and for performing the various operations in a manner that will produce the greatest safety to a workman operating the machine. The combined machine of this invention permits the wheel set to be positioned within the machine in a manner that the center of gravity of the counterweights of the wheel set is below the turning centers of the machine, and substantially in vertical alignment therewith. This arrangement provides the greatest safety of position for a wheel set when in a turning machine for the quartering and pin turning operations. The machine also provides for counter-balancing the unbalanced weight of the wheel set when turning the journals thereon, whereby a machine having the greatest safety conveniences is provided.

In this invention the machine consists of a bed 10 which is supported upon a suitable concrete base 11, and is adjusted to a level position by means of the wedge blocks 12. A head stock 15 is positioned upon the bed 10 and is adapted for longitudinal movement along the bed 10 to permit adjustment of the live spindle 16 thereof, with respect a wheel set. An electric motor 15a is mounted adjacent one side of the head stock 15 having the drive shaft extending into the same for driving suitable mechanism positioned within the head stock 15 for rotating the live spindle 16, which mechanism is well known in the art. A face plate 17 is adapted to be mounted upon the live spindle 16 for carrying counter-weights (not shown) for counter-balancing the unbalanced weight of the wheel set when turning the journals thereon. A suitable dog is provided for interconnecting the face plate with the wheel set for drivingly engaging the wheel set when turning the journals.

The live spindle 16 is connected by suitable mechanism with a hand wheel 19, which hand wheel advances the turning center of the spindle into engagement with the wheel set when positioned in the machine. There is also provided a suitable mechanism engaged by operation of the clutch lever 20 which engages mechanism interconnecting the hand wheel 21 with the spindle 16 in order to rotate the same and the face plate 17 for bringing the face plate into a particular position when using the machine for quartering a wheel set. A locking device 22 is mounted upon the head stock 15 and engages the face plate 17 to lock the same in position when quartering a wheel set.

A tail stock 25 is positioned upon the opposite end of the machine from the head stock 15. A supporting center or spindle 26 is suitably positioned within the tail stock 25 for engaging a wheel set, which spindle is advanced or retracted by suitable mechanism controlled by means of the hand wheel 27. The tail stock is movable longitudinally along the bed 10 and is locked in position upon the bed 10 by means of the clamping device 28. The head stock 15 is secured in its position upon the bed 10 by a similar clamping device 29.

A pair of carriage brackets 30 and 31 are secured to the bed 10 and are adapted to support a plurality of tool carriages 32. The tool carriages 32 are drivingly connected with a power driven rod 32a, which is connected by suitable power driven mechanism with the feed rod 31a for operating the carriages longitudinally along

the brackets 30 and 31. The feed rod 31a is drivingly connected to a power driven gear 32a, drivingly connected with the gearing in the head stock 15, by means of an interconnecting shaft 33a. A speed change mechanism 34a is interposed between the drive gear 32a and the feed rod 31a. The bracket 30 supports the tool carriages 32 when turning the inside journals of a wheel set while the bracket 31 supports a carriage 32 when turning an outside journal of a wheel set.

Each of the power driven carriages 32 support a cross slide 33 upon which a tool support 34 is positioned. The cross slide 33 may also be power driven or hand driven for transverse movement of the tool holder or support 34.

A wheel set 40 comprising an axle 41 and a pair of wheels 42 is adapted to be positioned between the live spindle 16 positioned upon the head stock 15 and the turning center positioned upon the tail stock 25.

When a wheel set is being turned there is considerable unbalanced weight upon the set due to the counter-balances provided thereon for balancing the connecting rod and operating mechanisms of a locomotive drive device. In order to balance this unbalanced weight of the wheel set when turning the journals thereon, a counter-balance weight is positioned upon the face plate 17 whereby the rotation of the wheel set is smooth and is without vibration. The tool carriages 32 are suitably adjusted with a tool 45 positioned within the tool holder 34 for removing the desired material from the axle 41 of the wheel set. The tool carriages 32 are power driven longitudinally along the axle 41 for removing material therefrom in the normal manner of lathe turning.

In order to provide for quartering the wheel set 40, a quartering device 50 is mounted upon the head stock 15 while a quartering device 60 is positioned adjacent the tail stock 25. The quartering attachment 50 is mounted directly upon the head stock 15 and consists of a driving motor 51 which provides power through the belt 52 into a gear housing 53. Suitable gearing is provided within the housing 53 for driving a boring spindle 54. The boring spindle 54 is arranged parallel with the axis of the live spindle 16, and is disposed in a plane passing through the axis of the spindle 16 which is arranged at an angle of 45° from a vertical plane passing through the axis of the spindle 16. The boring spindle 54 is thus positioned above the axis of the spindle 16 and at an accurate 45° angle therefrom.

The quartering device 50 is carried upon a support bracket 55 which has an angularly inclined face 56 upon which the quartering device is supported. The quartering device 50 is suitably arranged to be moved radially with respect the axis of the spindle 16 in order to position the boring spindle 54 at different radial distances from the spindle 16. A suitable adjusting screw 57 is provided for making the radial adjustment of the position of the quartering device 50. A hand wheel 58 provides means whereby a suitable mechanism, engaging the boring spindle 54, causes the spindle to be moved longitudinally by means of the hand wheel 58. The boring spindle 54 is also adapted to be power driven by the motor 51 through a suitable train of gears within the housing 53.

The quartering attachment 60 is supported upon a bracket 61 secured to the bed 10, which has an angular face 62. The angular face 62 provides means upon which a support 63 can be

moved radially by means of a suitable adjusting screw 64. The support 63 carries a suitable gear box 65 which interconnects an electric motor 66 with the spindle 67 for power driving the same. A hand wheel 68 also engages mechanism with the gear box 65 for manually advancing or retracting the spindle 67.

The spindle 67 is of the type known to the trade as a "pot type spindle." The spindle 67 consists of a hollow cylindrical member suitably bearinged in the quartering attachment 60 and is driven by the electric motor 66. The forward edge of the cylindrical member or spindle 67 is provided with T slots 69 in the face thereof by which a boring bar is secured thereto when quartering a wheel set, or for securing a turning tool thereto when turning the pins on a wheel set.

The spindle 67 is parallel with the turning center 26, and is disposed in a plane extending through the axis of the center 26 that is arranged at an angle of 45° to a vertical plane extending through the turning center 26.

It is thus seen that the boring spindles 67 and 54 are arranged above the axis of the live spindle 16 and the turning center 26, and that planes passing through the axes of the boring spindles 67 and 54, and the axes of the live spindle 16 and the turning center 26 form an angle of 90° with respect to one another, since the axis of each spindle 67 and 54 is disposed in a plane extending through the respective spindles and the axes of spindle centers 16 and 26 that form an angle of 45° with a vertical plane extending through the spindle centers 16 and 26.

The wheel set 40 is arranged to have the pin bores 71, located 90° apart in order to provide a lead of one wheel over the other. The counterweights 70 (Fig. 10), are provided for counterbalancing the weight of the pin, the connecting rod and other operating mechanisms, and are thus located 180° from the pin bores 71. It may thus be seen that since the boring spindles 54 and 67 are arranged above the axes of the turning centers 16 and 26 that the major portion of the counterweights 70 will be arranged below the turning centers 16 and 26 and that a plane passing through the centers of the counterweight sections and the wheel centers will be displaced 45° angularly from the vertical plane through the wheel centers when the wheel set 40 is supported between the turning centers. This arrangement thereby provides the safest position of the wheel set when in a machine for quartering the same since there is no tendency toward torque movement of the wheel set which would have a tendency to throw the set should an accident occur, the effective center of gravity of the wheel set being in substantial vertical alignment with the axes of the turning centers 16 and 26.

The boring spindles 54 and 67 may be operated simultaneously or successively depending upon the will of the operator since each device is under separate power. It is to be understood of course that the boring spindles 54 and 67 engage suitable mechanism within the gear housings 53 and 65 respectively for causing advancement of a boring tool through the pin bores 71. The operation may be carried out manually by means of the hand wheels provided on the respective quartering devices 50 and 60.

When positioning a wheel set within the combined machine for quartering, journal turning or pin turning, the wheel set 40 is elevated into position in axial alignment with the turning centers by means of tread jacks 80, which are po-

sitioned under each of the wheels of the wheel set 40. Since the center of gravity of the wheel set 40 is normally in its lowest position, as previously described, it may be seen that the wheel set 40 can be supported directly upon the tread jacks 80 without further support whereby the axle 41 of the wheel set can easily be brought into alignment with the turning centers 16 and 26. The turning centers 16 and 26 are then brought into engagement with the axle 41 to properly and accurately align the wheel set 40 with respect to the turning axis of the machine.

Either the quartering operation or the journal turning operation can then be performed. If the

15 journal turning operation is to be first performed the face plate 17 is counter-balanced as heretofore mentioned and the tool carriages 32 operated in conventional manner to remove excess material from the journals of the wheel set. Without 20 further alteration of the machine, the wheel set can be quartered by bringing the counter-balances thereof into their lowermost position thereby aligning the boring spindles with the roughly cast pin bores 71 in the wheel set 40.

25 In order to accurately align the pin bores 71 with respect to the boring spindles 54 and 67, an adjusting mechanism 85 is provided. This mechanism consists of a rotatable rod 86 which threadedly engages a collar 87. The collar 87 is pivotally mounted upon an arm 89 which is secured to the bed 10 by means of the bolts 90. The opposite end of the rod 86 extends through a C clamp 91 which is provided with set screws 92 in threaded engagement with the arms of the C clamp 91. The set screws 92 are in axial alignment and are adapted to engage the edge of the wheel 42 as indicated at 93 (Fig. 9) whereby the C clamp 91 is provided with a pivotal engagement with the wheel 42. The rod 86 is provided with 30 collars 94 positioned on either side of the C bracket 91 to position the same upon the rod 86. The upper end of the rod 86 is provided with a suitable rectangular or square shape which can be engaged by a wrench for rotating the rod 86 where 35 by the length thereof between the pivots 88 and 92 can be altered.

40 The wheel set 40 can thus be adjusted rotatably by means of the adjusting device 85 in order to accurately align the roughly cast pin bores 71 with respect to the boring spindles 54 and 67. Upon 45 making the above mentioned alignment the wheel set 40 is clamped against rotation by means of a clamping device 100.

A clamping device 100 is provided for each of 50 the wheels 42 of the wheel set. This clamping device consists of a supporting bracket 101 secured to the bed 10 by means of suitable bolts 102. The supporting bracket 101 has a pair of parallel T slots 103 positioned in the face 104 thereof. A bracket 105 is carried upon the face 104 by means of bolts 106 which extend through the bracket 105, and have the heads thereof engaging the T slots 103. The bolts 106 have suitable nuts 107 in threaded engagement with the ends thereof, for securing the bracket 105 upon the face 104 of the support 101. A threaded rod 110 is supported by means of a bracket 111 secured to the support 101 by means of the bolt 112. The threaded rod 110 is carried upon the bracket 111 by means of spacing collars 113. The rod 110 is in threaded engagement with an ear 114 extending from the bracket 105 whereby the bracket can be moved vertically with respect to the support 101 by rotation of the rod 110.

55 The bracket 105 consists of two parts, 105A and

105B, forming a split bearing around a transversely extended shaft 115. A binding screw 116 extends through the flanges 117 of the split bearing halves 105A and 105B, whereby the bearing halves are caused to bind upon the shaft 115. A C clamp 125 is pivotally mounted upon the shaft 115 as at 120, and is provided with a binding set screw 121 in the opposite end of the clamp.

Upon making the final accurate adjustment of the wheel set with respect the boring spindles 54 and 67 by means of the adjusting device 85, the shaft 115 of the clamp means 100 is brought into engagement with the inner face of the wheel 42. The binding screw is then tightened to retain the shaft 115 in position in engagement with the face of the wheel 42. It is to be understood of course that the shaft 115 has been brought into the proper horizontal position with respect the wheel 42 by means of the threaded rod 110 which has elevated the bracket 105 to the proper position. The bracket 105 has been secured to the support 101 by means of the nuts and bolts 107 and 106 respectively. The C clamp 125 is then brought adjacent the edge of the wheel 42 and the binding bolt drawn tightly against the outer face of the wheel, whereby the wheel is secured against rotation. It may be seen that the clamping devices 100 adjust themselves to the wheel spacing, rather than forcing the wheels to adjust themselves to the clamp spacing. This arrangement provides an apparatus which prevents any springing of the wheels and thereby permits more accurate boring of the pin bores 71 of the wheel set 40, and more accurate pin turning. The wheel set 40 is now in condition to be quartered. The boring spindles 54 and 67 are suitably advanced by the machine, or by manual means, for causing the desired boring or quartering operation, whereby the pin bores 71 are accurately spaced at a 90° angle from each other.

In the newer type wheel sets for locomotives the bearing housings are attached prior to the time the wheel set is quartered. This is particularly true in those instances where ball or roller bearings are installed upon the axle 41 of the wheel set. The wheel clamps 100, if made high enough to permit sufficient vertical adjustment of the C clamps to take care of small diameter wheels interfere with the bearing housings on large diameter wheels when positioned in the machine. Hence, when turning or quartering small diameter wheels the clamping device 100 must be elevated sufficiently to permit the effective use of the clamp 125. A spacer block 130 is thus provided between the bracket 111 and the support 101 (Fig. 8). In this instance the bracket 111 is bolted to the spacer block 130 by means of the bolt 112A, while the spacer block 130 is secured to the support 101 by means of a flange 131 positioned thereon engaging a flange 132 provided on the support 101 (Fig. 4). A suitable bolt 133 extends through the flanges 131 and 132 to secure the same together.

As heretofore mentioned the wheel set 40 is adapted to be elevated into position in alignment with the turning centers 16 and 26 by means of a tread jack rather than by means of an axle jack as has been heretofore common practice in the art. The use of tread jacks has been required due to the positioning of bearing housings upon the wheel sets prior to the time they are quartered. The arrangement of posi-

tioning the wheel set 40 within the machine with the center of gravity in vertical alignment with the axes of the turning centers 16 and 26 provides a particularly advantageous arrangement for the use of tread jacks, since the wheel set will balance itself upon the jack.

The jack as provided in this invention consists of a shoe 150 which is secured upon the end of a threaded rod 151. The rod 151 carries a nut 152 which is positioned within a supporting housing 153 upon a thrust bearing 154. The support housing 153 is carried within a recess 154A provided in the bed 10 of the machine. The nut 152 has a spiral gear 155 secured thereon, which is in engagement with a spiral gear 156. The gear 156 is in turn in communication with an operating shaft 157 which extends exteriorly of the bed 10 and is provided with a wrench connection 158 on the exterior end thereof. Rotation of the shaft 157 will cause the nut 152 to be rotated by means of the spiral gears 155 and 156 whereby the threaded rod 151 is raised or lowered to carry the wheel set thereby.

The quartering and journal turning operations have heretofore been described. The crank pin turning operation can also be performed upon this combined machine of my invention. It is of course understood that after the quartering and journal turning operations the wheel set 40 is removed from the machine in order to permit the placement of crank pins within the pin bores 71. After this operation, the wheel set 40 is returned to the combined machine of my invention. The wheel set is positioned upon the tread jacks 80 and hoisted into position with the axis of the wheel set in alignment with the axes of the turning centers. The clamping devices 100 are again positioned in operative relation with the wheels 42 of the wheel set 40 to prevent rotation of the wheel set. The wheel set 40 is adjusted rotatably by means of the adjusting device 85 in order to properly align a crank pin with respect to the axis of the boring spindle 67. As heretofore described, the boring spindle 67 is known to the trade as a "pot type spindle." A suitable turning tool is secured within the spindle 67 by suitable fastening means engaging the T slots 69. The boring spindle 67 is then advanced either automatically or manually by the quartering attachment 60 so as to turn the surface of the crank pin in alignment therewith.

Since the machine is provided with only one "pot type spindle" 67, the wheel set is required to be repositioned so as to bring the crank pin of the opposite wheel into alignment with the spindle 67. While the machine as disclosed in the drawings requires two positionings of the wheel set 40 in order to turn both crank pins thereon, it may readily be understood that both of the boring spindles 67 and 54 could be of the "pot type."

There are certain disadvantages however in making the boring spindle 54 of a "pot type" spindle since the spindle 54 is required to extend through the face plate 17 when quartering the wheel set or when the spindle 54 is to be used for pin turning. The normal procedure is to permit the boring spindle 54 to extend through an opening (not shown) in the face plate 17, the face plate 17 of course, being brought to a predetermined position by operation of the hand wheel 21 in order to permit the boring spindle 54 to

extend through the opening provided in the face plate 17.

It may thus be seen that my combined machine provides all of the necessary operations for finishing the journals, crank pins and for quartering a wheel set, which machine is flexible for working upon various size wheel sets, and which positions the wheel set in the machine in a manner which produces the least danger to a workman engaged thereupon.

While the apparatus herein disclosed constitutes the preferred form of the invention yet there are other forms which will fall within the scope of my invention and I do not wish to be limited by the specific disclosure herein described.

Having thus fully described my invention, what I claim as new and desire to secure by Letters Patent, is:

1. A machine for quartering of wheel sets comprising a bed, a head stock carrying a spindle, a tail stock carrying a support center, a boring spindle carried by the head stock, a second boring spindle carried by the tail stock, said boring spindles being positioned parallel with the axes of the spindle and the support center and above the same in planes inclined upwardly in opposite directions from said axes and displaced 45° from a vertical plane through said axes.

2. In a quartering machine for locomotive wheel sets, a bed, a head stock, a tail stock, support centers in said head and tail stocks, quartering mechanisms mounted on said head and tail stocks, means for positioning a wheel set in position for quartering, and means for clamping the wheel set in position, said last mentioned means having a floating clamp to permit adjustment thereof to the wheel spacing.

3. A machine for producing quartering operations upon a wheel set comprising a bed, a head stock, a tail stock, means for supporting a wheel set between said head and tail stocks and clamp means for clamping said wheel set against rotation comprising a clamp movable into engagement with a wheel, means for securing said clamp in position in engagement with said wheel and means carried by said clamp for securing the same to the wheel.

4. A clamp for use on a metal working machine for wheel sets comprising a support, a bar carried upon said support and movable longitudinally and transversely thereof, means for securing said bar in longitudinal position, means for securing said bar in transverse position and a wheel clamp carried by said bar.

5. A clamp for use on a metal working machine for wheel sets comprising a support, a bar carried upon said support and movable longitudinally and transversely thereof, means for securing said bar in longitudinal position, means for securing said bar in transverse position and a wheel clamp pivotally carried upon said bar.

6. A clamp for use on a metal working machine for wheel sets comprising a support, a bar carried upon said support and movable longitudinally and transversely thereof, means for securing said bar in position in engagement with a wheel of a wheel set, and a wheel clamp carried by said bar.

7. A clamp for use on a metal working machine for wheel sets comprising a support, a bar carried upon said support and movable longitudinally and transversely thereof, means for adjustably moving said bar in one of said directions, means for securing said bar against movement in the direction of adjustment after made,

said bar being still freely movable in the other of said directions for further adjustment, means for securing said bar against movement in the last mentioned direction after adjustment is made, and clamp means carried by said bar for clampingly engaging a wheel.

8. In a machine for quartering locomotive car sets comprising a bed, a bracket mounted upon said bed, a tool carriage positioned upon said bracket for longitudinal movement thereon, a head stock and a tail stock positioned upon said bed, means for supporting a wheel set between said head stock and tail stock, a boring spindle carried by said head stock, a boring spindle carried by said tail stock, said boring spindles being arranged parallel with the axis of the supporting means for the wheel set and arranged in a plane angular with respect the vertical plane extending through the supporting means for the wheel set, said angular planes being inclined upwardly from the axis of support for the wheel set, and mechanisms for driving said boring spindles whereby said wheel set can be quartered when in said machine with the counterweights thereof arranged with the effective center of gravity in vertical alignment with the wheel set supporting means.

9. In a machine for quartering locomotive wheel sets, a bed, longitudinally movable tool carriages, a head stock and a tail stock, a quartering attachment positioned on said head stock and having a boring spindle extending therefrom arranged in a plane inclined upwardly from the spindle of the head stock at an angle of 45° and parallel with said spindle, a quartering attachment carried by said bed adjacent said tail stock having a spindle extending therefrom in a plane upwardly inclined from the spindle of the tail stock at an angle of 45° and parallel thereto, said spindles being displaced 90° apart and with their axes above the axes of the head and tail stocks, whereby a wheel set can be quartered in the machine with the counterweights thereof positioned below the axes of the head and tail stock spindles and with the effective center of gravity thereof in vertical alignment therewith.

10. A machine for quartering of locomotive wheel sets comprising a bed, a head stock, a quartering attachment carried by said head stock with a boring spindle extending therefrom in a plane inclined upwardly from the spindle of the head stock and parallel thereto, a quartering attachment carried by said bed and adjacent said tail stock having a spindle with its axes arranged in a plane extending upwardly at an angle of 45° from the spindle of the tail stock and parallel thereto.

11. In a metal working machine for locomotive wheel sets, a bed, a head stock, a tail stock, means for supporting a wheel set between said head stock and said tail stock and means for rotatably adjusting the wheel set comprising a pivotally mounted adjustable length rod, and clamp means carried by said rod for providing a pivotal mounting thereof upon a wheel.

12. In a metal working machine for locomotive wheel sets, a bed, a head stock, a tail stock, means for supporting a wheel set between said head stock and said tail stock and means for rotatably adjusting the wheel set comprising an adjustable length rod pivotally mounted upon said bed, a clamp carried by said rod, means for pivotally connecting said clamp upon a wheel, and means for adjusting the length of the rod for rotatably adjusting the wheel set.

13. A machine for quartering of wheel sets

comprising a bed, a head stock carrying a spindle, a tail stock carrying a support center, a quartering attachment carried by said head stock having a boring spindle extending therefrom, a quartering attachment positioned adjacent the tail stock and having a spindle extending therefrom, said latter two spindles adapted to receive the boring

tools, and being positioned parallel with the axes of the head stock spindle and the support center, and above the same in planes inclined upwardly in opposite directions from said axes and displaced 45° from a vertical plane through said axes.

AUGUSTUS WOOD,
